UNITED STATES PATENT OFFICE.

WILLIAM JOSEPH PERRY, OF LONDON, ENGLAND, ASSIGNOR TO THE INDIA RUBBER
GUTTA PERCHA & TELEGRAPH WORKS COMPANY LIMITED, OF LONDON, ENGLAND.

DESIGN FOR A GOLF BALL.

Application filed October 2, 1928, Serial No. 28,349, and in Great Britain July 13, 1928. Term of
patent 14 years.

To all whom it may concern:

Be it known that I, WILLIAM JOSEPH PERRY, a subject of the King of England, residing at "Milestone", Shooter's Hill, London, S. E. 18, England, have invented a new, original, and ornamental Design for a Golf Ball, of which the following is a specification, reference being had to the accompanying drawing, forming part thereof.

The figures are respectively a view looking

squarely at one pole of the golf ball; a view looking down on the golf ball shown in the preceding figure; and a view looking from a position to one side of the top figure, illustrating my new design.

I claim—

The ornamental design for a golf ball as shown.

WILLIAM JOSEPH PERRY.
